UNITED STATES PATENT OFFICE

ANGUS F. HANNEY, OF NORWOOD, OHIO, ASSIGNOR TO THE AMERICAN LAUNDRY MACHINERY COMPANY, OF NORWOOD, OHIO, A CORPORATION OF OHIO

LAUNDRY MARKER DETACHER

Application filed February 24, 1930. Serial No. 431,002.

My invention relates to apparatus for detaching metal identification clips from laundry goods. It is particularly applicable for use in detaching such clips after the goods have been laundered and are being prepared for delivery to the customer. However, the apparatus may be used for detaching marking clips at any time.

Heretofore, specially constructed pliers or tools have been used to remove the metal identification clips from laundered goods, the marking clip used being made of spring sheet metal bent into a U-shape and having its free ends normally closed by the inherent resiliency of the clip and contacting with each other between which a portion of the piece of goods is held. Such method of removing the clips is slow and tedious work and does not provide a means for automatically checking the goods in a bundle or act as a check on the operator's error. Further, such method does not require that the marking clip be on its proper key bar before removal from the goods and does not provide any means for preventing the operator from removing an improper clip at any time. That is, it does not prevent the operator from removing a clip from a piece of goods that belongs to another bundle.

One object of my invention is to provide an apparatus for separating the free ends of the marking clips and maintaining the ends in such position so as to permit goods to be removed from between such ends.

Another object of my invention is to provide a means for limiting the distance to which the free ends of the marking clip are separated.

Still another object of my invention is to provide a means for locking the apparatus against operation until the marking clips are in their proper position in the machine and to provide means for locking the machine against improper operation on the clips or operation on improper clips.

Still another object of my invention is to provide a device which is easily operated and does not require that the operator be skilled in the art of removing clips from laundered goods.

Various other objects and advantageous features of my invention may be seen in the following detailed description and one embodiment thereof may be seen in the accompanying drawings wherein similar characters of reference designate corresponding parts, and wherein:

Fig. 1 is an elevation of the left hand side of a device constructed in accordance with my invention.

Fig. 2 is also an elevation showing operating parts seen from the right hand side of my machine, parts of the machine being broken away.

Fig. 3 is a plan view of the device.

Fig. 4 is a fragmentary view showing the means for operating the device.

Figs. 5, 6, and 7 are sectional views showing the parts for operating upon the marking clips in various positions.

Fig. 8 is a view showing the capability of movement of the jaw block with relation to the floating bar.

With reference to the drawings, the support for the device comprises a base made up of radially extending legs and feet 1 equipped with roller elements 2 and a central hub 3 having a vertical bore to receive a tubular post or upright member 4 carrying two shelf members 5 and 6 for the goods being operated upon. The shelf member 5 is equipped with a rack 7 in which a supply of empty clip key bars may be stored prior to use in the machine.

One of the legs of the base portion embodies a bracket 8 having a vertical bore for the reception of a tubular post 9 which supports substantially all of the working mechanism with the exception of a foot lever 10 that is pivotally connected as at 11 to suitable depending lugs 12 on one of the leg members 1.

The lever 10 is pivotally connected intermediate its ends as at 18 to a lever 13 extending at right angles to the lever 10 and having its short-arm pivotally connected as at 14 to depending ears 15 in one of the leg members 1 and its longer arm pivotally connected as at 16 to the lower end of a link 17 whose upper end is pivotally connected as at 25 to the low-

er end of a vertically movable cam plate 26, the purpose of which will be hereinafter described. Such link 17 is also connected to a spring 27 connected at its opposite end to a bracket 28 on the tubular post 9. With this construction, the foot lever 10 moves downwardly against the resistance of the spring 27 and is moved upwardly by the action of such spring.

- 10 The cam plate 26 is mounted in guide-ways 27' in the upper portion of the apparatus which is preferably made separately from the tubular upright member 9 for purposes of manufacture and attached thereto by any well known means and a suitable retainer plate 29 holds the cam plate within such guides. Such cam plate 26 is moved downwardly by the foot lever 10 and upwardly by the action of the spring 27 and embodies a cam slot 30 for operating one part of the device and a cam slot 31 for operating another part thereof.

One of these parts consists of a clamping member 40 that is adapted to engage the bent rounded end on each marking clip and is stationary as respects vertical movement. The other part consists of an upper jaw member 34 that is capable of being moved horizontally, vertically, and angularly, in the same vertical plane.

The clamping member 40 is rigidly secured to the upper side of a sliding member 35 that is reciprocable horizontally in suitable guide-ways by the vertical reciprocation of the cam-plate 26. Such reciprocation of the member 35 is the result of movement of a roller 36 secured to the member 35 along the length of the cam slot 30 when the cam plate 26 is moved upwardly or downwardly. A lower jaw member 32 is rigidly secured to the upper part of the machine frame and is adapted to engage the lower jaw socket 33.

Immediately in front of the jaw member 32 is a stop device 37 pivotally mounted on a pin 39 and having its lower bifurcated end engaging a horizontally disposed pin 38 in the forwardmost end of the member 35, and being so disposed that its upper end will be in a horizontal plane coinciding to the plane of the jaw member 32 when in operative position, and will be below such plane when in inoperative position. The stop member is moved to operative position wherein it engages and moves the clip onto the jaw member 32 by the forward movement of the member 35 resulting from the action of the cam slot 30 on the roller 36 when the cam plate 26 is moved downwardly.

The upwardly extending clamping member 40 is disposed on the member 35 a short distance to the rear of jaw member 32 and in a plane above such jaw member. When in idle position, the spacing of the extension 40 from the jaw member 32 and the spacing of the stop 37 from the jaw 32 is such that when

a marking clip is placed in position with the jaw member 32 extending into the jaw socket 33 on the clip, the extension 40 is not quite in contact with the bent rounded end of the clip and the top end of the stop 37 is slightly below and in front of the protruding portion of the jaw socket on the clip. This is clearly illustrated in Figs. 5 and 7 of the drawings.

However, when the member 35 is moved forward by downward movement of the cam plate 26, the extension 40 will move forwardly to and engage the rounded end of the marking clip and the pin 38 will swing the uppermost end of the stop 37 rearwardly to such position that it will contact with the outer surface of the jaw socket 33 and move such jaw socket onto the jaw member 32, whereby the marking clip will be secured and firmly clamped between the stop 37 and the extension 40 on the member 35.

As shown in Figs. 5, 6 and 7, the surface of the extension 40 which contacts with the rounded end of the marking clip is of such contour as to prevent the marking clip from slipping upwardly and out of contact with the extension while the end of the clip opposite its rounded end is prevented from moving upwardly by the jaw member 32 disposed within the lower jaw socket 33 of the marking clip.

The upper jaw member 34 is secured to the forward end of a jaw block 41 pivotally mounted at the front end of a floating bar 42 that is pivotally connected at its rearward-most end as at 43 to one free end of a bell crank lever 44 and pivotally connected at its forwardmost end by means of a pin 45 to the ends of links 46. The links 46 are, in turn, pivotally mounted, as at 47, to a bearing block 48 that is rigidly mounted on the top portion of the apparatus and in a plane above the sliding member 35. As shown, the pin 45, by means of which the links 46 are connected to the floating bar 42 extends through the links 46, the forward forked end of the floating bar 42, and the jaw block 41 to serve as a pivotal mounting for the jaw block.

The jaw block 41 is yieldably held as shown in Figs. 5, 6, 7 and 8, against the front end of the floating bar 42 which acts as a stop therefor by the coiled contracting spring 49. With this construction, the jaw block 41 will be positively moved clockwise about its pivot by the clockwise movement of the floating bar 42 but will be yieldably moved counter-clockwise by a counterclockwise movement of the floating bar to permit the upper jaw member 34 to yield by pivoting about the pin 45 in the event that the clip, with which it is supposed to engage, is improperly placed in position when the operator depresses the foot lever 10. Thus, a means is provided for preventing breakage of parts.

The bell crank lever 44 is pivotally mounted as at 50 to a bracket 51 rigidly mounted on an

upper horizontal surface of the device and extending upwardly therefrom. Also, the free end of the remaining arm of the bell crank lever is provided with an anti-friction roller 52 so disposed as to extend into the cam slot 31 in the cam plate 26 whereby vertical movement of the cam plate 26 by the mechanism hereinbefore described will cause movement of the floating bar 42 through the medium of the link connections just described. That is, the upper jaw member 34 will be moved from its normal position first downwardly, then forwardly, and then upwardly, when the cam plate 26 is moved downwardly, the reverse taken place when the cam plate 26 is moved upwardly. The jaw member 34 will be moved into the upper jaw socket 53 of the marking clip at the same time that the clip is being moved into position relative to the sliding member 35 and the subsequent movement of the clamping member 40 will spread the free ends of the clip, as shown in Fig. 6.

To furnish a guide underneath which the clip to be detached must be moved and to prevent the marking clip from having its free ends moved too far apart, a guard 54 is adjustably secured on the upper surface of the floating bar 42, as shown in Figs. 5, 6 and 7, and is of such shape and so positioned that its forwardmost end will bear against the upper free end of the marking clip when the machine is in an operated position.

In the laundry checking system using the marking clip adapted to be detached from the goods by this apparatus, it is advantageous that means be provided for preventing operation of the device unless the marking clip is one of a given set. To accomplish this feature, the key bar on which a given set of marking clips may be disposed takes a definite part in the operation of this device. That is, the machine is provided with mechanism which will lock it against operation unless the marking clip to be removed is adapted to fit upon a particular key bar being used.

A pivoted angular locking bar 55 is provided and is so mounted that its free end is normally positioned under the lower end of the cam plate 26 to prevent downward movement of said plate. As shown in Fig. 2, the locking bar 55 is pivoted as at 56 to a bracket 57 rigidly secured on the tubular post 9. A short distance from the pivot 56 of the locking bar a link 58 is pivotally connected thereto which extends downwardly and is pivotally connected as at 59, see Figs. 1 and 4, to the free end of an arm 60 rigidly secured on a rock shaft 61 mounted in a suitable bearing formed in a spanner 62 clamped around the tubular post 9 but not adjustable along the length of the post.

When the rock shaft 61 is moved counterclockwise, Fig. 1, the free end of the arm 60 and the link 58 will be moved downwardly whereby the free end of the locking bar 55

will move to the right in an arcuate path about its pivot point 56 and the end of such bar, which is normally disposed under the cam plate 26, will be moved outwardly to such position that the cam plate may be moved downwardly. In a like manner, when the rock shaft 61 is moved clockwise, the locking bar will be moved to its normal position under the lower end of the cam plate 26 and downward movement of the cam plate 26 will be prevented, as will downward movement of the foot lever 10.

In order to prevent any pressure applied to the foot lever 10 from being transmitted to the pivot 56 when the locking bar is in normal locked position, such locking bar is provided with a bearing surface 63 that is oppositely disposed from the surface contacted with by the lower edge of the cam plate 26 when such cam plate is moved downwardly. The bearing surface 63 is adapted to rest on a lug 64 that forms an integral part of the bracket 57.

A socket 65 is made rigid with rock shaft 61 and arm 60, and a key bar 66 is adapted to fit within such socket to act as a lever for moving the rock shaft 61 in either direction. Spring 66' normally holds the parts in the position shown in Fig. 1 with the upper end of the key bar 66 disposed a short distance to the front of the upper and lower jaw members 34 and 32 whereby the operator may conveniently slide the cooperating part of a marking clip secured to the piece of goods onto the upper end of such key bar and the goods may be moved downwardly and rearwardly together with the marking clip until the goods rest upon the top surface of the device so that the marking clip is in alignment with the cooperating jaw members and its lower jaw socket 33 is moved onto its jaw 32. A slot 67, see Fig. 3, is provided in the upper horizontal part of the device so that the marking clip may be moved into its proper position with relation to the jaw members and the open end of such slot is preferably made flaring so as to make it easier to insert the upper end of the key bar into such slot.

Since the key bar serves as a lever for moving the locking bar 55 into or out of such position that it will prevent downward movement of the cam plate 26 and consequently prevent the operation of the device, it will be seen that the device can not be operated until the upper end of the key bar 66 is moved within the slot 67. Further, since the marking clip is to be disposed on the key bar prior to the key bar being moved within the slot 67 it will be readily seen that a positive means has been provided for locking the device against operation unless the marking clip on the piece of goods held by the operator will fit upon the particular key bar 66 which rests within the socket 65.

In the operation of the device, assuming that the marking clip is adapted to fit upon the particular key bar resting in the socket 65, the marking clip is first placed upon the key bar with the goods still attached thereto and the key bar moved within the slot 67. Thus the locking bar 55 is moved to such position that it will not prevent operation of the device. Then, the foot lever 10 is moved downwardly and the cam plate 26 moved in the same direction resulting in the forward movement of the sliding member 35 to clamp the clip as above described and the downward and forward movement of the forward end 15 of the floating bar 42 to move the upper jaw member 34 into cooperative relation with its jaw socket 53 of the marking clip.

Continued downward movement of the cam plate 26 serves to move the forward end of the jaw block 41 and the jaw 34 upwardly to spread the free ends of the marking clip, as shown in Fig. 6, whereupon the goods will be removed from the clip. Then, release of the foot lever 10 from the force exerted thereon will permit upward movement of the cam plate 26 through the action of the spring 27 and the reverse movement of the various parts. Thus, the jaw member 34 will be moved down to close the clip and then out of its jaw socket 53 of the marking clip and the key bar 66 will be moved clockwise, see Fig. 1, out of the slot 67 by spring 66' to again position the locking bar in its normal position under the lower end of the cam plate 26.

On removal of a piece of goods from the clip and the return of the key bar to normal position such clip will gravitate down the key bar adjacent the lowermost end thereof or against the uppermost clip thereon.

It will be readily understood that it is absolutely necessary that the marking clip be placed in position in the machine with its lower jaw socket 33 disposed over the lower jaw 32 and with the clip wedged between the stop member 37 and the upstanding member 40 in order that the machine may function properly with regard to the clip. To insure such placing of this clip, a stop is provided which takes the form of a forwardly extending arm 68 made integral with one of the links 46, having a laterally extending portion 69 on its extreme outer end in the manner shown in Figs. 1, 2, 3, 5, 6, and 7, and is of such nature that when the links 46 move 55 in a counter-clockwise direction Figs. 2, 5, 6 and 7, the outwardly extending arm 68 will likewise move in the same direction. The length of the arm 68 is such that, if the key bar 66 is not disposed in proper position within the slot 67 which is provided therefor, the laterally extending portion 69 will strike the upper end of the key bar and prevent further operation of the device. However, when the key bar 66 is properly disposed within the slot 67 the laterally extending portion 69 of

the arm 68 will pass to the front of the key bar 66 and the arm 68 moves downwardly with the free ends of links 46. Thus, it will be seen that I have provided a means for locking the machine against operation until the marking clip is in its proper position therein.

An adjustable stop 70 is provided on the bracket 57 in such position as to be in the path of the lower end of the cam plate 26 and serves to limit the downward movement of the cam plate when the foot lever 10 is depressed and is made adjustable so that the downward movement of the cam plate may be varied as to distance and the degree of upward movement of the upper jaw 34 can be adjusted to separate the free ends of the clip as desired. Further, an adjustable stop 71 is provided on one of the radially extending legs 1 to limit the upward movement of the foot lever 10 and thereby limit the degree of upward movement of the cam plate 26 and the distance to which the guard 54 and the upper jaw 34 is raised in its normal position. A sheet metal shield 72 indicated by dotted lines in Figs. 1 and 3, is preferably provided to guard against an unscrupulous person manipulating the locking bar 55 in the absence of a key bar 66.

Referring to the drawings and the preceding description it will be seen that I have provided a device embodying numerous novel and advantageous features. For instance, I have provided a mechanism for separating the normally contacting ends of a marking clip so that the goods may be removed from between such free ends and have provided a stop for normally preventing operation of this device. In this device, the stop is effective unless the marking clip to be removed belongs to a predetermined group and unless the marking clip is in the proper position relative to the mechanism for removing it. Another advantageous feature resides in the fact that means have been provided for adjusting the mechanism to spread the normally contacting free ends of a clip to any desired extent and for preventing breakage of parts of the mechanism should the marking clip be defective or should any foreign article find its way into the mechanism.

What I claim is:

1. Apparatus for separating the free ends of a clip which includes adjacent legs, comprising a support, a jaw adapted to engage one of the legs of said clip, a jaw adapted to engage the other leg of said clip, mechanism carried by said support for moving said jaw members into engagement with the legs of said clip and then moving one of said jaw members relative to the other to separate the free ends thereof, and locking means for normally preventing operation of said mechanism.

2. Apparatus for separating the free ends of a clip which includes adjacent legs, com-

prising a support, a jaw adapted to engage one of the legs of said clip, a jaw adapted to engage the other leg of said clip, mechanism carried by said support for moving said jaw members into engagement with the legs of said clip, clamping said clip in place, and then moving one of said jaw members relative to the other to separate the free ends thereof, and locking means for normally preventing operation of said mechanism.

3. Apparatus for separating the free ends of a clip which includes adjacent legs, comprising a support, a jaw adapted to engage one of the legs of said clip, a jaw adapted to engage the other leg of said clip, mechanism carried by said support for moving said jaw members into engagement with the legs of said clip and then moving one of said jaw members relative to the other to separate the free ends thereof, and locking means for normally preventing operation of said mechanism, said last named means embodying a lock movable to ineffective position by proper positioning of a marking clip in said apparatus.

4. Apparatus for separating the free ends of a clip which includes adjacent legs, comprising a support, a jaw adapted to engage one of the legs of said clip, a jaw adapted to engage the other leg of said clip, mechanism carried by said support for moving said jaw members into engagement with the legs of said clip and then moving one of said jaw members relative to the other to separate the free ends thereof, locking means for normally preventing operation of said mechanism, said last named means embodying a lock movable to ineffective position by proper positioning of a marking clip in said apparatus, and a clip key bar in association with said apparatus and adapted to render said locking means ineffective when a marking clip is placed thereon and moved to proper position within said apparatus.

5. Apparatus for separating the free ends of a clip which includes adjacent legs, comprising a support, a jaw adapted to engage one of the legs of said clip, a jaw adapted to engage the other leg of said clip, mechanism carried by said support for moving said jaw members into engagement with the legs of said clip and then moving one of said jaw members relative to the other to separate the free ends thereof, locking means for normally preventing operation of said mechanism, said last named means embodying a lock movable to ineffective position by proper positioning of a marking clip in said apparatus, and a clip key bar in association with said apparatus and adapted to render said locking means ineffective when a marking clip is placed thereon and moved to proper position within said apparatus, and a stop for preventing effective operation of said mech-

anism until said key bar and clip disposed thereon are properly positioned.

6. Apparatus for separating the free ends of a clip which includes adjacent legs, comprising a support, a jaw adapted to engage one of the legs of said clip, a jaw adapted to engage the other leg of said clip, mechanism carried by said support for moving said jaw members into engagement with the legs of said clip and then moving one of said jaw members relative to the other to separate the free ends thereof, locking means for normally preventing operation of said mechanism, and means for automatically returning said mechanism to its normal unoperated position after operation thereof.

7. Apparatus for separating the free ends of a clip which includes adjacent legs, comprising a support, a jaw adapted to engage one of the legs of said clip, a jaw adapted to engage the other leg of said clip, means for holding one of said jaws stationary, mechanism effective to move said other jaw through an arcuate path to separate the free ends of said clip, and locking means for normally preventing operation of said mechanism.

8. Apparatus for separating the free ends of a clip which includes adjacent legs, comprising a support, a jaw adapted to engage one of the legs of said clip, a jaw adapted to engage the other leg of said clip, means for holding one of said jaws stationary, mechanism effective to move the other of said jaws downwardly, forwardly and then upwardly to separate the free ends of said clip, and locking means for normally preventing operation of said mechanism.

9. Apparatus for separating the free ends of a clip which includes adjacent legs, comprising a support, a jaw adapted to engage one of the legs of said clip, a jaw adapted to engage the other leg of said clip, a cam element movable to effect engagement of one of said jaw members with one leg of said clip and then relative to the other jaw member to separate such free ends, means for moving said cam element in one direction, and locking means for normally preventing operation of said cam element.

10. Apparatus for separating the free ends of a clip which includes adjacent legs, comprising a support, a jaw adapted to engage one of the legs of said clip, a jaw adapted to engage the other leg of said clip, a cam element movable to effect engagement of one of said jaw members with one leg of said clip and then relative to the other jaw member to separate such free ends, means for moving said cam element in one direction, locking means for normally preventing operation of said cam element, and means for automatically returning said cam element to its normal position.

11. Apparatus for separating the free ends of a clip which includes adjacent legs, com-

prising a support, a jaw adapted to engage one of the legs of said clip, a jaw adapted to engage the other leg of said clip, mechanism carried by said support for moving one of said jaw members into engagement with one leg of said clip and then relative to the other jaw member to separate the free ends of said clip, means for adjusting the mechanism to effect spreading of the free ends of a clip to a greater or less degree, and locking means for normally preventing operation of said mechanism.

In testimony whereof I hereby affix my signature.

18**ANGUS F. HANNEY.****20****25****30****35****40****45****50****55****60****65**
